(57) **CLAIM**

(21) Appl. No.: **29/244,997**

The ornamental design for a hook rod and slide fastener for support of conduit, cable, wire and the like, as shown and described.

(22) Filed: **Dec. 15, 2005**

DESCRIPTION

Related U.S. Application Data

(60) Provisional application No. 60/665,017, filed on Mar. 25, 2005.

FIG. 1 is a first side elevation view of the hook rod and slide fastener for support of conduit, cable, wire and the like showing my new design;

(51) **LOC (8) Cl.** **08-05**

FIG. 2 is a front elevation view of the invention thereof;

(52) **U.S. Cl.** **D8/370**

FIG. 3 is a second side elevation view thereof;

(58) **Field of Classification Search** D8/370,
D8/367; 248/302-303; 174/79; 24/129 R,
24/136 R

FIG. 4 is a rear elevation view thereof;

See application file for complete search history.

FIG. 5 is a top view thereof; and,

FIG. 6 is a bottom view thereof.

(56) **References Cited**

The broken line showing of structure is for illustrative purposes only and forms no part of the claimed design.
